OR 12,226

No 12,226

April 12, 1881

UNITED STATES PATENT OFFICE.

CHARLES PENCHARD, OF LONG ISLAND CITY, ASSIGNOR TO WILLIAM M. WATSON, JOHN M. KARSCH, AND WILLIAM E. WATSON, OF NEW YORK, N. Y.

DESIGN FOR A CHAIR.

SPECIFICATION forming part of Design No. 12,226, dated April 12, 1881.

Application filed March 12, 1881. Term of patent 3½ years.

To all whom it may concern:

Be it known that I, CHARLES PENCHARD, a citizen of the United States, residing at Long Island City, in the county of Queens and State of New York, have invented and produced a new and original Design for Chairs; and I do hereby declare that the following is a full, clear, and exact description thereof.

This invention relates more particularly to 10 the chair-back or portion above the seat, and it may be applied to chairs of various descriptions, without regard to the style of seat or legs.

In the accompanying photographic illustration, A represents the shield or main surface 15 of the back.

B B are the back-posts, which are beaded longitudinally and vertically, and their upper ends terminate in tapering spindles b b.

C is the top rail of the chair-back. It is curved 20 in the form of an arc of a circle. Its ends are decorated with buttons or arabesques d, and on its front surface is an ornamental carving, e.

F F² are the upper and lower rails of the shield, and they are beaded longitudinally and 25 horizontally. The ends of the tapering spindles b join the lower edge of the top rail, C, and between said lower edge of said top rail, C, and the upper edge of the upper rail, F, of the shield are short spindles G, having swells and beads 30 turned on them.

To the lower edges of the ends of the top rail, C, are joined the upper ends of the arms H H, which are curved gracefully downward and forward, and have the sides of their front ends decorated with buttons or arabesques i, beneath which they are joined by the upper ends of stumps or spindles J, having swells and beads turned on them. 35

I claim as my invention—

1. The design for a chair back and shield 40 herein described, consisting of the back-posts B, beaded longitudinally and vertically, and terminating in spindles b, and the rails F F², beaded longitudinally and horizontally, and the spindles G, having swells and beads turned 45 on them, as herein set forth.

2. The design for a chair back and arms herein described, consisting of the top rail, C, having its ends decorated with buttons d, and its front surface with a carving, e, the curved arms 50 H, decorated with buttons i, and the stumps or spindles J, having swells and beads turned on them, as herein set forth.

CHAS. PENCHARD.
